Inventor,

Thomas H. Settle,
By Elmer P. Flynn
Attorney.

UNITED STATES PATENT OFFICE.

THOMAS H. SETTLE, OF LOS ANGELES, CALIFORNIA.

WAVE-MOTOR.

No. 901,489.

Specification of Letters Patent.

Patented Oct. 20, 1908.

Application filed August 3, 1908. Serial No. 446,577.

To all whom it may concern:

Be it known that I, THOMAS H. SETTLE, a citizen of the United States, residing in the city of Los Angeles, county of Los Angeles, 5 and State of California, have invented new and useful Improvements in Wave-Motors, of which the following is a specification.

My invention relates to means for utilizing the projectile power of waves on the 10 surface of a body of water for the purpose of running machinery, and the object thereof is to provide simple and efficient and automatically readjusted mechanism for that purpose. I accomplish this object by the 15 mechanism described herein and illustrated in the accompanying drawings, in which;

Figure 1 is a side elevation partly in section of my improved power mechanism. Fig. 2 is a plan of the parts shown in Fig. 1.

20 In the drawings I have shown only a portion of the wharf mechanism, the balance being omitted for clearness of illustration. Outer piles 5 are driven in the bed of the body of water a suitable distance from the 25 shore thereof and upon these piles is secured a superstructure 6, upon which superstructure are bearings 7 in which is revolvably mounted power shaft 8. Upon the outer end of power shaft 8 is the transmission pulley 9 around which the transmission cable 10 runs to the driven machinery not shown. Upon the power shaft near the ends thereof are loosely mounted sheaves 11. These sheaves carry dogs 12 which engage 30 with ratchets 13 rigidly secured upon the power shaft and form a clutch. Upon sheaves 11 are received cables 14 which are preferably wound with one or more turns around the sheaves. To the outer ends of 35 cables 14 are secured the takeup weights 15 which prevent slack forming in the cable in the operation of the device. The inner ends of cables 14 are secured to the power apron 16 at the ends and at the lower edge 40 thereof. These power aprons are as long and as wide as may be desired to produce the necessary power and will be proportioned to the strength of the waves at the point where used. Secured to the upper 45 edge and at each end of the power apron are the supporting arms 17 in the upper ends of which are mounted grooved pulleys 18. These pulleys travel upon cables 19 which are secured to the inner piles 20 at 50 one end and to the outer piles at the other end. Cables 19 are secured at a higher ele-

vation on the inner piles than on the outer piles so that the tendency of the pulleys 18 is to travel toward the outer piles, thereby carrying the power apron toward the outer 60 piles.

In the operation of my device the waves will be rolling from the direction of the outer piles to the inner piles and will impinge against the power apron and carry the 65 same along with it toward the shore. As the power apron moves toward the shore it rotates the power shaft to drive cable 10 in the direction indicated by the arrow thereby operating the driven mechanism. When the 70 force of the wave has been spent the undertow together with the weight of the power apron and the pitch of the supporting cables 19 will cause the power apron to travel back toward the outer piles to meet the next in- 75 coming wave.

In practice there would be a plurality of power aprons to operate at different distances from the power shaft so as to produce a continuous steady power upon the 80 power shaft at all times. I have shown only one power apron as one is all that is necessary to illustrate the principles in my invention.

Having described my invention what I 85 claim is:

1. A wave motor comprising a power apron; a power shaft; clutch mechanism secured upon said power shaft; cables running over said clutch mechanism and secured to the power apron; means secured to said cables to take up the slack thereof; supporting means for the upper portion of said power aprons, said supporting means being set at an angle to cause the travel of 90 the power apron toward the power shaft; and means to utilize the revolutions of the power shaft.

2. In a wave motor a traveling power apron; a power shaft; means to cause a 100 travel of the power apron toward the power shaft; means connected to the power apron and the power shaft to revolve the power shaft upon the travel of the power apron away from the shaft; and means to utilize 105 the revolutions of the power shaft.

3. In a wave motor a power shaft; means to support said shaft at a distance from the shore; clutch mechanism secured upon said power shaft; cables secured to said power shaft supporting means; means for supporting the other ends of said cables at a higher 110 elevation.

elevation; a power apron; cables running from the lower edge of said power apron to and around the clutches on the power shaft; counterbalancing weights on the ends of said 5 least cables; supporting arms secured to the ends of said power apron; pulleys mounted in the upper ends of said arms arranged to travel upon the cables running from the power shaft supporting means toward the

shore; and means to utilize the revolutions of the power shaft.

In witness that I claim the foregoing I have hereunto subscribed my name this 29th day of July, 1908.

THOMAS H. SETTLE.
